LIGHTER

Emile Gilberton, Paris, France, assignor to Etablissements Genoud et Cie, Societe Anonyme

Filed Feb. 2, 1961, Ser. No. 63,801

Term of patent 7 years

Claims priority, application France Nov. 25, 1960

(Cl. D48—27)

FIG. 1 FIG. 2 FIG. 3

FIG. 4

FIG. 2 is an elevational view taken from the left of FIG. 1;

FIG. 3 is a similar view taken from right of FIG. 1; and,

FIG. 4 is a top plan view thereof.

The flat U-shaped element on the top of the lighter, which has a conventional criss-cross pattern, is slightly recessed with respect to the top thereof.

I claim:

The ornamental design for a lighter, as shown and described.
